UNITED STATES PATENT OFFICE.

ABBIE L. SILBERMAN, OF NEW YORK, N. Y.

DESIGN FOR A HAND-BAG OR SATCHEL.

SPECIFICATION forming part of Design No. 14,464, dated December 4, 1883.

Application filed October 5, 1883. Term of patent 3½ years.

To all whom it may concern:

Be it known that I, ABBIE L. SILBERMAN, of New York, in the county of New York and State of New York, have invented a new and 5 original Design for Hand-Bags, Satchels, &c., of which the following is a specification.

My design relates to hand-bags and satchels and other like articles; and the design consists in the representation thereon of a butter- 10 fly, with the wings extended across lengthwise of the article.

The accompanying illustration is a perspective view of a hand-bag embodying my design. The upper portion of the outer wall is orna- 15 mented with the representation of a butter-

fly, B, which is so arranged that the wings extend between the ends of the bag, or, in other words, lengthwise of the bag.

What I claim as my design, and desire to secure by Letters Patent, is—

The design for a hand-bag, satchel, or other like article, consisting in a representation of a butterfly thereon, with the wings extended lengthwise of the article, substantially as shown and described. 20
